FIG. 1.

FIG. 2.

FIG. 4.

FIG. 5.

FIG. 6.

INVENTOR
THOMAS BOND
By *John Starkey Jr.*
ATTYS.

UNITED STATES PATENT OFFICE.

THOMAS BOND, OF BRANTFORD, ONTARIO, CANADA.

BANK CAGE.

Application filed August 18, 1923. Serial No. 658,140.

To all whom it may concern:

Be it known that I, THOMAS BOND, a subject of the King of Great Britain, and a resident of the city of Brantford, in the 5 county of Brant, in the Province of Ontario, Canada, have invented certain new and useful Improvements in Bank Cages, of which the following is the specification.

My invention relates to improvements in 10 bank cages and the object of the invention is to devise manually controlled means for releasing the shutter which is spring actuated into the closed position in front of the cage for protecting the occupant from being 15 held up by bank robbers.

A further object is to devise improved means whereby the raising of the shutter will automatically actuate releasing means which normally holds bullet proof side curtains for protecting the sides of the cage. 20

A still further object is to devise means whereby the springs which impel the shutter upwardly will act as buffers therefor when the shutter reaches its uppermost position. 25

Another object is to devise improved means for resetting the shutter when it has been once actuated.

My invention consists of a bank cage 30 constructed and arranged all as hereinafter more particularly described and illustrated in the accompanying drawing in which:

Fig. 1 represents a vertical cross sectional view of a cage looking towards the front, 35 showing the shutter and side curtains in the inoperative position.

Fig. 2 is a similar view to Figure 1 showing the shutter and side curtains in the operative or protecting position.

Fig. 3 is a vertical section through the 40 line 3—3 Figure 1.

Fig. 4 is an enlarged vertical section through the line 4—4 Figure 1.

Fig. 5 is a vertical sectional detail of a 45 portion of the actuating means for releasing the side curtains.

Fig. 6 is a longitudinal section of one of the side curtain housings broken away intermediately and illustrating the means for 50 normally holding the door thereof in position.

Like characters of reference indicate corresponding parts in the different views.

1 is the cage provided with the usual 55 grids 2. 3 is the shutter which is constructed of bullet resisting material and is adapt-

ed to slide vertically on the tracks 4 secured to the inner face of the side posts 5 of the cage, said shutter adapted to extend through a slot 6 in the counter 7. 8 are vertically disposed spring receiving housings adapted to be secured to the posts 5 and provided with lower vertical slots 9 and upper vertical slots 10 in the forward face of such housing. 60

11 and 12 are respectively upper and lower cylindrical slide blocks adapted to slide in the housing 8, each upper block 11 provided with a forwardly directed pin 13 extending forwardly through the corresponding slot 10 and each block 12 provided with a similar pin 14 extending forwardly through the slot 9. 15 are springs, each secured at its upper end to the block 11 and at its lower end to the block 12. 16 is a rib 70 on the inner face of the bottom of the shutter 3.

17 is a vertically disposed toothed rack 80 provided on the rear face of the shutter 3 and adapted to engage the pawl 18, pivotally connected to the forward end of the actuating lever 19 which is fulcrumed at 20 in the vertically disposed standard 21 mounted on the floor of the cage in rear of the shutter 3. 22 is a weight actuated pawl 85 pivotally secured in the standard 21 and adapted to engage the teeth of the rack 17. 23 is a laterally extending bar hinged to the sides of the cage 1 by the hinge 24, said bar 23 having pivotally connected to its forward face the forwardly extending rod 25, which is in turn pivotally connected at its forward end to the lower end of the pivotally mounted dog 26 which is adapted to engage the teeth of the rack 17. 27 is a laterally 90 extending rod journaled in the bearings 28 on the side posts 5 of the cage, said rod carrying the depending arm 29 which is pivotally connected at its lower end to the rearwardly extending rod 30 journaled in the bearing 31, the rear end of the rod 30 being provided with the actuating lever 32.

33 are brake arms secured intermediately of their length to the rod 27 and their lower ends connected by means of the chains 34 with the dogs 35 which are pivotally mounted on collars 36 on the spring receiving standards, each of said dogs having a stepped shutter engaging face. 105

37 are collapsible side curtains of bullet 110 proof material secured at their tops in the housings 38 provided with the hinged bot-

tom doors 39. 40 are eyes provided on the upper faces of the doors in the vicinity of their free edges, said eyes adapted to be engaged by the hooked ends of the latches 41 which are pivotally mounted in the housings 38, the upper ends of said latches being pivotally connected to the longitudinally extending rod 42 journaled in the housing. 43 is a spring interposed between the rear latch 41 and the rear end of the casing, said spring being freely mounted on the rod 42. The forward end of the bar protrudes freely through the forward face of the housing. 44 are arms pivotally mounted in recesses 45 in the side face of the corner posts 5, said arms normally inclined outwardly to engage the forward ends of the rod 42 and hold them in their rearmost position wherein the latches 41 engage the eyes 40 of the doors 39.

The operation of my device is as follows: Upon the shutter being set in the position illustrated in Figure 3 and it being desired to raise the same, the bar 23 is kicked by the occupant of the cage which will push forward the rods 25, thus releasing the dog 26 from the rack and allowing the shutter to be impelled upwardly by means of the springs 15. This is achieved owing to the fact that the springs have been distended on the downward movement of the shutter into the particular position by the lugs 14 coming into contact with the bottom of the shutter. As the shutter 3 reaches its uppermost position the rib 16 engages the upper pins 13, thus tending to distend the springs in an upward direction, thereby constituting a buffer for stopping the upward movement of such shutter. 40 As the shutter travels upwardly it engages the arms 44, forcing their free ends forwardly until they are out of engagement with the ends of the rods 42, which permits the rods to be forced forwardly under the influence of the springs 43, releasing the latches 41 from the eyes 40 and allowing the doors 39 of the side curtain housings to drop. This releases the curtains 37 and permits them to assume the closed position illustrated in Figure 2 of the drawing.

After the lower edge of the shutter 3 passes up beyond the dog 35, such dog falls forwardly, thus preventing the shutter falling again into the open position, until the dog is released.

To lower the shutter the lever 32 is pulled rearwardly and through the medium of the pivoted arm 29 pulls rearwardly the dog 35 out of engagement with the bottom edge 60 of the shutter, permitting the same to drop until the lower edge thereof comes into engagement again with the pins.

Simultaneously with this action, the brake arm 38 is thrown forwardly by the arm 29 until its free end engages the rear face of

the shutter, thus braking it in its downward movement.

When it is desired to reset the shutter, the lever 19 is actuated so that the pawl 18 engages the teeth of the toothed rack 17 and as the lever is lifted upwardly the shutter will be correspondingly lowered, the weighted pawl 22 preventing retrograde motion of the shutter as the lever is actuated in an upward direction, the leg 46 on the forward end of the lever 19 engaging the lug 47. The leg 46 prevents such pawl 22 from engaging the rack 17 when the lever is in the position illustrated in Figure 3.

The side shutters are replaced by hand in the housings 38 and the doors 39 closed, the arms 44 being reset in engagement with the forward rods 42.

What I claim as my invention is:

1. In a bank cage, the combination with the front thereof, of a vertically slidable bullet proof shutter, means for pulling the shutter down into its normal position, releasable means for normally holding the shutter in the normal position, a tension spring having its lower end provided with a projection adapted to engage the bottom edge of the shutter when in the normal position, and its upper end provided with an extension adapted to engage said shutter upon the latter being thrown upwardly. 90

2. In a bank cage, the combination with the front thereof, of a vertically slidable bullet proof shutter, means for pulling the shutter down into its normal position, a vertical casing, upper and lower slide blocks slidable in the casing, a tension spring being mounted therebetween, lugs on said blocks projecting from the casing, the lug on the lower block adapted to engage the lower edge of the shutter upon its being in the normal position, and the lug on the upper block adapted to engage the shutter upon the latter being thrown upwardly. 105

3. In a bank cage, the combination with the front thereof, of a vertically slidable bullet proof shutter, means for pulling the shutter down into its normal position, a vertical casing having upper and lower slots, upper and lower slide blocks slidable in the casing, a tension spring being mounted therebetween, lugs on said upper and lower blocks projecting through the slots and slidable therein, a stop secured to the shutter in the vicinity of its lower end, the lug on the lower block being adapted to engage the lower edge of the shutter upon its being in the normal position, and the lug on the upper block adapted to engage the said stop upon the shutter being thrown upwardly. 115

4. In a bank cage, the combination with the front thereof, of a vertically slidable bullet proof shutter, a rack secured to the shutter, a lever mounted interiorly of the

- cage in the vicinity of the rack, and means on the lever for engaging the rack and depressing the shutter down into its normal position, a tension spring, means on the 5 lower end of the spring engaging the shutter upon its being in the normal position, and means on the upper end of the spring for engaging the shutter upon the latter being thrown upwardly.
- 10 5. In a bank cage, the combination with the front thereof, of a vertically slideable bullet proof shutter, a rack secured to the shutter, a lever mounted interiorly of the cage in the vicinity of the rack, a pawl 15 mounted on the lever and adapted to engage the rack and depress the shutter into its normal position, a vertical casing, a tension spring mounted therein, upper and lower slide blocks slideable in the casing, lugs on 20 said upper and lower blocks projecting through the slots and slideable therein, a stop secured to the shutter in the vicinity of its lower end, the lug on the lower block adapted to engage the lower edge of the 25 shutter upon its being in the normal position, and the lug on the upper block adapted to engage the said stop upon the shutter being thrown upwardly.
6. In a bank cage, the combination with 30 the front thereof, of a vertically slideable shutter, means for throwing the shutter up into the closed position covering the exposed front of the cage, collapsible bullet proof side curtains normally retained in their 35 folded position, housings normally holding such curtains in their folded position, bottom doors swingably mounted in the housings, eyes on the inner faces of the doors, spring actuated rods slideable in the housings, latches on the rods adapted to engage 40 the said eyes and retain the doors in the normally closed position, and means engaged by the shutter for disengaging the latches from the eyes to allow the curtains to drop into their closed position covering the exposed 45 sides of the cage.
7. In a bank cage, the combination with the front thereof, of a vertically slideable shutter, means for throwing the shutter up into the closed position covering the exposed 50 front of the cage, collapsible bullet proof side curtains normally retained in their folded position, housings normally holding such curtains in their folded position, bottom doors swingably mounted in the 55 housings, eyes on the inner faces of the doors, spring actuated rods slideable in the housings, latches on the rods adapted to engage the said eyes and retain the doors in the normally closed position, arms pivotally mounted on the front of the cage having their free ends engaging the ends of the rods and retaining the latches in engagement 60 with the eyes, the shutter being designed to disengage the arms from the rods upon its being thrown upwardly and to disengage the latches from the eyes and allow the curtains to drop into their closed position.

THOMAS BOND.
